UNITED STATES PATENT OFFICE

JOHN JOSEPH McCALL, OF PHILADELPHIA, PENNSYLVANIA, ASSIGNOR OF ONE-HALF
TO DAVID N. SAFRAN

SELF SEALING TUBE AND PROCESS OF MAKING THE SAME

Application filed June 2, 1928. Serial No. 282,497.

This invention relates to an improved pneumatic tube, a new plastic composition which may be used therewith and a new method of manufacturing such tube and composition.

The tubes at present in use are defective for the reason that no provision is made for the prevention of blowouts and punctures with the consequent possibility of injury when such an event occurs.

Although many attempts have been made to solve this problem, yet there are few, if any, tubes on the market at present which have specific provisions to prevent punctures or blowouts, or at least reduce the possibility of such occurring. The reason for this condition is found in the cost of manufacture of such tubes, in the character of the composition used, in the difficulty of manufacture and assembly of the component parts, or in any combination of the above causes.

It is the applicant's purpose to produce a tube which shall be comparatively easy to manufacture and assemble and to produce a filling composition which shall be easy and cheap to manufacture, easy to apply and which shall be efficient.

More particularly stated, one of the purposes of my invention is to produce a pneumatic tube which shall be self healing in the event of a puncture.

Another object of my invention is to produce a pneumatic tube which shall greatly obviate the possibility of the occurrence of blowouts and punctures.

Another object of my invention is to produce a pneumatic tube having an inner guard.

Another object of my invention is to produce a pneumatic tube having an inner guard which guard shall be separated from the remaining portion of the tube by an air space.

Another object of my invention is to produce a pneumatic tube having an inner guard which guard shall be separated from the remaining portion of the tube by a filler.

Another object of my invention is to disclose a method of making the said pneumatic tube.

Another object of my invention is to produce a composition, or filling, for the inner tubes, or tires, whereby the same may be self healing in the event of a puncture, or blowout.

Another object of my invention is to disclose a method of making the said composition.

Although the disclosure as herein described will show the composition used in association with my new tube structure, yet it is to be distinctly understood that this is merely the preferred form and by the way of illustration only.

In conjunction with my new tube structure any kind of filling composition, which need not necessarily be the filling composition herein disclosed, may be used. Also, my filling composition may be used with any kind of tube structure which need not necessarily be the same as that herein disclosed. The use of either the composition alone or the tube structure alone is within the scope of my invention. The use of both together as herein shown is at present believed to give the best results. But, it is realized by the inventor that the new composition herein disclosed may be used in conjunction with any type of tube structure, and that the tube structure herein shown may be used either alone or in combination with any kind of filling composition without departing from the scope or spirit of this invention.

With the above cited and other objects reference is now had to the following disclosure and the drawings to which they refer for the purpose of clearly bringing out my invention.

In the drawings Figure 1 shows a tube on a mandrel and illustrates the first step in my process of the structure of my tube.

Figure 2 is a section through the mandrel.

and tube, showing only the tube, and illustrates the second step in the process of constructing my tube.

Figure 3 is a section taken similarly to 5 Figure 2 showing the completed tube while it is still on the mandrel and illustrates the third step in my process of constructing the tube.

Figure 4 is a section on the line 4—4 of 10 Figure 5, and illustrates a section of the completed tube after it has been removed from the mandrel and turned to present the proper surface on the outside.

Figure 5 shows a completed tube viewed 15 from the outside.

Figure 6 is a partial section of the tube similar to the lower portion of the tube shown in Figure 4, purposely enlarged for the purpose of more clearly bringing out the structure of the tube.

Referring more particularly to the drawings, reference number 1 shows the completed tube; 2 the outer tube or component of the same; 3 the mandrel upon which the tube is made; 4 a layer of adhesive used to connect the composition to the outer tube; 5 a filling composition; 6 the ensemble of layers of air and flexible substance interposed between the coating composition and the inner guard; 7 20 the inner guard and 12 the air valve.

The outer tube 2 serves the same purpose and considered alone is the same as the ordinary tube now in general use.

The filling composition 5 serves as a self 35 acting medium which goes into, or is forced into, the hole caused by a puncture in the tube and serves to fill the gap.

The flexible substance 11 serves to separate the inner guard 7 from the filling composition 40 5. It further serves to prevent the inner guard 7 from adhering to the filling composition 5. It further serves to help maintain the air space, or spaces, between the filling composition 5 and the inner guard 7. The flexible substance may be paper, as herein shown, 45 or tin foil, or any other substance which has the properties of flexibility, ease of rupture and non-adhesiveness to either the substance of the inner guard 7, the filling composition 5, or both. The flexible substance may be merely placed between the filling composition 5 and the inner guard 7, but not cemented or otherwise fixedly attached to either, as herein shown, or it may be fixedly attached 50 by cement or otherwise to either the filling composition 5 or the inner guard 7, but not to both. If it is unattached to either, as herein shown, two (2) air spaces 8 are formed. If attached to either the inner guard or the 55 filling composition only one (1) air space is formed. It is my desire and object, however, to always have at least one air space between the filling composition 5 and the inner guard 7.

60 The inner guard 7 combines with the outer

tube 2, the filling composition 5 and the flexible substance 11 to bound and form the air spaces 8. The inner guard further serves as an additional wall to keep the puncturing material from penetrating the tube proper. The inner guard further serves as an additional cover for the punctured surface. The inner guard may be of vulcanized flexible rubber, similar to that composing the outer tube 2, or it may be some other air proof flexible and expandable material.

The inner guard 7 serves to keep the filling composition 5 concentrated at the bottom or tread portion of the tire. Were it not present the pressure of the air in the tube 70 would force the filling composition to spread over the entire inner surface of the tube, thus thinning the same at the tread where it is really needed. The inner guard 7 further serves to keep the composition 5 from direct 75 contact with the upper wall of the tube in the event of a puncture.

The air space or chamber 8 serves to make the action of the filling composition positive.

The air space or chamber 8 further serves 80 as a medium which, by adding a certain thickness to the wall of the tube, serves to keep the puncturing material from penetrating the tube proper.

My process of making the tube is as follows:

I take an ordinary pneumatic tube of cured or vulcanized rubber made according to any one of the methods now in use, turn it inside out and mount the same upon a mandrel 3; 100 the pneumatic tube constitutes the outer tube 2. I then apply a layer of vulcanizing cement 4 over the entire length and practically half the circumference of the outer tube 2. I then apply a layer of filling composition 5 over the said vulcanizing cement covering the entire length of the tube.

The cement 4 serves as an adhesive to connect the filling composition 5 to the outer tube 2. I then place a layer of paper, or 110 filler, 11 upon the filling composition 5 over the entire length of the tube. The paper layer 11 serves, among other things, to prevent the inner guard from becoming stuck and attached to the filling composition 5. 115 Then at 9—9, a little beyond the point where the filling composition ends, I apply another coat of vulcanizing cement over the entire length of the tube. I then place thereon the guard in such a manner that the ends 13—13 120 of the guard 7 fall upon the layer of vulcanizing cement at 9—9, thus joining the inner guard to the outer core at 9—9. Since the inner guard 7 is only joined to the tube at the points 9—9, the part of the inner guard 7 125 between the two edges 9—9 is free to move in relation to the surface of the paper layer 11 and the filling composition 5. The above structure results in air spaces 8 between the filling portion 5, the paper layer 11 and the 130

inner guard 7. The tube is now removed from the mandrel 3 and turned inside out in any one of the methods now well known in the trade. A valve 12 is inserted in the tube and fixed thereto in the manner well known in the art and the ends 10-10 are joined in a manner well known in the trade, completing the tube and giving us the final product shown in Figure 5.

10 The above disclosure is to be understood as by the way of illustration only and not by the way of limitation since many variations may be made in the character of the material used and even in the method of assembly of the components without departing from the spirit and scope of my invention. For instance, instead of using a vulcanized tube which has been removed from the mandrel we can start with the tube as it comes 15 from the vulcanizing process which, although vulcanized or cured, is still upon the mandrel. Instead of placing the paper or its equivalent directly upon the filling composition 5, the same may be inserted between the 20 filling composition 5 and the inner guard 7 after the tube is removed from the mandrel. Instead of using cured rubber for the inner guard, some other equivalent substance may be substituted therefor. Instead of using vul- 25 canizing cement, some other equivalent cement might be used. Or, instead of turning the tube inside out after the coating composition 5, the filler 11 and the inner guard 7 have been attached thereto, the ensemble could 30 be removed from the mandrel without turning the same inside out and the tube finished by inserting the air valve and joining the edges 35 10 in the manner well known in the art. This would result in a tube having the inner guard 7 as part of the outer wall. A cross section 40 through the finished tube of such a modification would be exactly like Figure 3 of the annexed drawings.

Definitions.—The word flexible and expandible material as used in the specification and claims is used to denote broadly flexible vulcanized rubber or any other substance from which pneumatic tubes or the inner guard may be constructed.

50 The words "flexible material" as used in the specification and claims is used to denote broadly a substance such as paper or tin foil which has the properties of flexibility, ease of rupture and nonadhesiveness to either the 55 substance of the inner guard 7, the filling composition 5, or both.

Having described a method of constructing my tube and the tube structure, I will now proceed to describe the filler which I use in 60 combination therewith.

I break down smoked sheet rubber and crepe rubber individually, then take seventy (70) pounds of the broken smoked sheet rubber, ten (10) pounds of the broken crepe rubber, and mix the two together in the rollers

for about twenty (20) minutes. Then I add ten (10) pounds of rosin and ten (10) pounds of pitch and continue mixing for ten (10) minutes until the desired consistency is obtained.

This results in the filling composition, the components of which are the following ingredients by per cent:

	Per cent
Rosin	10
Pitch	10
Smoked sheet rubber	70
Crepe rubber	10

The above is to be understood as by the way of illustration only and not by the way of limitation, since slight variations in the percentages of the desired substances may be used without departing from the spirit of my invention, or securing a composition which, in general, has the same qualities and characteristics as those given by the preferred formula.

Having described my invention what I claim as new and useful is:

1. A pneumatic tube comprising in cross-section an annular ply of vulcanized rubber, a strip of filling composition directly attached to the said annular ply for a substantial portion of its surface and a strip of flexible and expandible material overlying the said strip of filling composition spaced therefrom and attached at its edges to the said annular ply to divide the said pneumatic tube into a primary air chamber formed by the said flexible and expandible strip and the said annular ply and a permanently sealed safety air chamber formed by the said filling composition and the said flexible and expandible strip, the said primary air chamber having an inlet valve formed therein.

2. A pneumatic tube comprising in cross-section an annular ply of vulcanized rubber, a strip of filling composition attached to the said annular ply for a substantial portion of its surface, a strip of flexible and expandible material overlying the said strip of filling composition, spaced therefrom and attached at its edges to the said annular ply to divide the said pneumatic tube into a primary air chamber formed by the said flexible and expandible strip and the said annular ply and a permanently sealed safety air chamber formed by the said filling composition and the said flexible and expandible strip, the said primary air chamber having an inlet valve formed therein, and a strip of flexible material interposed between the said filling composition and the said flexible and expandible strip.

3. A pneumatic tube comprising in cross-section an annular ply of flexible and expandible vulcanized rubber, a strip of filling composition attached to the said annular ply for a substantial portion of its inner surface

and a strip of flexible and expansible vulcanized rubber overlying the said strip of filling composition spaced therefrom and attached at its edges to the said annular ply
5 to divide the said pneumatic tube into a primary air chamber formed by the said annular ply and the said flexible and expansible strip and a permanently sealed safety air chamber formed by the said filling
10 composition and the said flexible and expansible strip, the said primary air chamber having an air inlet valve formed therein.

4. A pneumatic tube comprising in cross-section an annular ply of flexible and expansible vulcanized rubber, a strip of filling composition attached to the said annular ply for a substantial portion of its surface, a strip of flexible and expansible vulcanized rubber overlying the said strip of filling composition, spaced therefrom and attached at its edges to the said annular ply to divide the said pneumatic tube into a primary air chamber formed by the said annular ply and the said flexible and expansible strip and a permanently sealed safety air chamber formed by the said filling composition and the said flexible and expansible strip, the said primary air chamber having an inlet valve formed therein, and a strip of flexible material interposed between the said filling composition and the said flexible and expansible strip.

5. A pneumatic tube comprising in cross-section an annular ply of flexible and expansible vulcanized rubber, a strip of filling composition attached to the said annular ply for a substantial portion of its surface, a strip of flexible and expansible vulcanized rubber overlying the said strip of filling composition, spaced therefrom and attached at its edges to the said annular ply to divide the said pneumatic tube into a primary air chamber formed by the said annular ply and the said flexible and expansible strip and a permanently sealed safety air chamber formed by the said filling composition and the said flexible and expansible strip, the said primary air chamber having an inlet valve formed therein and a strip of paper interposed between the said filling composition and the said flexible and expansible strip.

In witness whereof I hereby affix my hand,
April 30, 1928.

JOHN JOSEPH McCALL
